CARBURETOR

Marion Mallory, Detroit, Mich., assignor to The
Mallory Research Company, Toledo, Ohio, a
corporation of Delaware

Application April 28, 1934, Serial No. 722,977

10 Claims. (Cl. 261—34)

This invention relates to a carburetor, provided with a choke valve, and is in the nature of an improvement over the disclosure in my earlier application, Serial No. 702,051, filed December 12, 5 1933. The opening of the choke valve is controlled in part by suction from the intake manifold and in part by the velocity of the air passing through the carburetor.

The primary object of the invention is to effect 10 a more complete atomization of the fuel which passes into the cylinders. The air which is drawn into the cylinders passes the main fuel nozzle at high velocity, thereby drawing fuel into the main stream and completely atomizing it. The 15 throttle itself is a part of the venturi and, in the present form, comprises two oppositely opening valves with fuel nozzles therein, so that the fuel is always discharged toward the center line of the intake passage. The greatest restriction of 20 air flow and consequently the highest velocity is directly across the fuel nozzles. The fuel is therefore atomized as it is drawn through the venturi or throttle. After leaving the nozzles, the atomized fuel does not subsequently strike any wall, 25 as is the case with other carburetors, but passes directly into the center of a region of comparatively high vacuum, which tends to perfect the atomization.

The preferred form of the invention will now 30 be described more in detail in connection with the accompanying drawings, in which,—

Figure 1 is a vertical section taken centrally 35 of the intake passageway, with the choke valve closed.

Figure 2 is a central vertical section taken at right angles to the plane of Figure 1, showing 40 the choke valve open.

Figure 3 is a plan view of the carburetor.

Figure 4 is a section taken on the line 4—4 of 45 Figure 2.

Figure 5 is a detail view of the throttle control.

Figure 6 is a plan view of the throttle valves and connections.

The invention is herein shown as applied to a 50 down draft carburetor having a chamber 10 with an air inlet 11, within which is an annular seat 12 for the choke valve 13. The valve 13 is adapted to be opened by suction from the intake manifold, to which the lower end of the intake passageway 14 is adapted to be connected. For this 55 purpose, the chamber 10 is formed with a web 15 from which a hollow stem 16 extends upwardly and constitutes a bearing on which the valve 13 is reciprocably mounted. The valve 13 is formed internally with a suction chamber 17 and a light

spring 18 within the chamber 17 urges the valve toward its seat 12. A tube 19 connects the chamber 17 with the intake passageway 14. A cam or eccentric 20 is secured to a spindle 21 extending horizontally across the air intake 11 and the spindle 21 is adapted to be rocked by any known means, either manual or automatic, to hold the choke valve 13 positively open or partly open whenever the motor is warm enough to take a leaner mixture.

At one side of the intake passageway 14, there is a bowl 22, within which the liquid gasoline is maintained at a substantially constant level by the usual float 23 and needle valve 24 controlling the inlet to the bowl.

The throttle comprises two valves 25 mounted on parallel horizontal spindles 26, which are connected to each other at one end by intermeshing gear segments 27, so that they rock in opposite directions in their opening and closing movements. The valves 25 are balanced so that the vacuum on one side does not tend to hold them open. The walls of the intake passageway conform to the paths described by the outer edges of the valves 25, as shown at 28, so that all of the fuel which is drawn into the manifold passes between the valves along the center line of the passageway.

As the air is drawn through the chamber 10 and the passageway 14, gasoline is drawn into the air stream from the bowl 22. For this purpose, each spindle 26 has a depending tubular fuel inlet nozzle or dipper 29 extending below the liquid level in the bowl 22. The fuel passes from the nozzles or dippers 29 longitudinally of the respective spindles 26, which are also tubular, and through bores 30 in the valves 25, whence it is discharged into the air stream which passes downwardly through the chamber 10 when the throttle is open.

One of the valves 25 has a jet orifice 31 near its tip and another orifice 32 at its center. The orifice 32 acts as an air bleed to the jet orifice 31 when the throttle is opened to a small extent, thus causing more fuel to be discharged, but as the throttle is opened wider, the increased air flow is more directly across the orifice 32 and the latter ceases to be an air bleed. If the throttle is opened still wider, fuel is discharged from the orifice 32, as well as from the orifice 31. The orifices 31 and 32 are so restricted that the mixture will be sufficiently lean during the first stages of throttle opening. The other valve 25 has a larger opening 33 at its center which comes into operation only when the throttle is fully open or nearly

so, because it is pointed upward and there will be no vacuum created in it until it is turned into the air stream substantially at a right angle thereto. The orifice 43, therefore, plays the role 5 of a power jet.

An idling well 33 is formed in the wall of the passageway 14 and has an outlet 34 and bleed 35.

In the present construction, the throttle valve itself constitutes a venturi. In other words, with

- 10 the choke valve 13 open, the opening between the valves 25 is the most restricted part of the intake passageway and consequently the air flow at this point attains its highest velocity. This not only draws gasoline from the bowl but completely 15 atomizes it. The atomized fuel mixture then passes downwardly along the central line of the passageway directly into a region of high vacuum without striking any cold or hard surface, which would tend to condense it again.
- 20 In fuel feeding devices, as heretofore used, the volume of the fuel charge is usually controlled by a throttle valve having a single vane which deflects the fuel mixture against the side of the passageway. Thus the fuel, if it has become 25 atomized in the mixing chamber, tends to condense in drops, to be again atomized as it enters the region of high vacuum in the intake manifold. In the present construction, however, the initial atomization, which is more complete than 30 in the usual carburetor, is retained in full and is further promoted by the projection of the stream directly into the center of the high vacuum in the intake manifold.

It will be noted that in the present construction, as the throttle is opened, the jet orifices are 35 swung downwardly, so that there is an increased flow of gasoline from the bowl 22 in proper proportion to the increased flow of air. Thus the fuel mixture is regulated by the throttle without 40 the use of metering valves.

When the choke valve 13 is used, if the engine is operating at low speed and is suddenly accelerated, the pressure within the lower end of the passageway 14 will rise, permitting the choke 45 valve to move toward closed position. This maintains a degree of vacuum in the manifold, which will not only suck out more gasoline from the bowl but will at the same time promote its atomization.

50 I have found, however, that if the spring 18 alone is used in controlling the valve 13 and is made strong enough to choke the engine sufficiently for starting, it will be too stiff when the engine is running normally; that is, when the engine is accelerated and the vacuum decreases, the valve will close up too much and over-choke the engine. I have therefore provided a weaker auxiliary spring 44 mounted in a cup 45 at the top of the valve 13. This spring 44 opposes the 55 spring 18, when the cam 20 is moved to partially or wholly open the choke, thus preventing the valve 13 from over-choking the engine on acceleration. When the cam 20 is moved to choke the engine, however, the spring 44 is released.

60 In connection with this carburetor, I prefer 65 to use the throttle control device shown in Figure 5. In this device, the throttle lever 36 is secured to one of the spindles 26 and is connected to a piston 37 which operates in a dash pot 38. In closing the throttle, the manually operated rod 39 engages the lever 36 and a check valve 40 in the end of the dash pot allows the piston to move 70 freely therein, but in moving the rod 39 to open the throttle, it merely releases the lever 36. The throttle is then slowly opened by the air passing

therethrough. This opening will be facilitated if the valves 25 are unbalanced, with the greater area at the inner side of the axis. During this gradual opening movement of the throttle, the piston 37 gradually travels toward the open end 5 of the dash pot, while air bleeds into the dash pot through the bleed hole 42. Thus it is impossible to stall the engine by opening the throttle too suddenly.

From the foregoing description, it will be seen 10 that I have provided a fuel supply device in which the throttle itself constitutes a venturi and the gasoline is fed from the bowl through the throttle directly into the venturi, so that the highest air velocity is directly across the fuel jet nozzles, thereby insuring the best possible atomization. There is no throttle between the venturi and the intake manifold for the atomized fuel to strike against and to become again condensed, as is the case with the usual carburetors. All of 15 the air, as well as the fuel, is directed by the throttle toward the center line of the passageway and immediately into the region of highest vacuum.

20 While I have illustrated and described the specific form of the invention which at present seems most desirable, it is apparent that many of the details thereof may be considerably modified without departing from the scope of the 25 appended claims.

I claim:

1. In a carburetor, a fuel passageway, a throttle therein constituting a venturi, and means for discharging fuel in intersecting jets along the center line of said venturi, the angle between the jets being adjustable in synchronism with the adjustment of the throttle opening.

2. In a carburetor, a fuel bowl, an intake passageway, a throttle valve pivotally mounted in said passageway, a fuel jet nozzle in the throttle valve and connected with the bowl and discharging into said passageway at a point higher than the normal level of liquid in the bowl, the nozzle outlet being on the side of the valve axis which moves downwardly as the valve opens.

3. In a carburetor, a passageway having a variable venturi, a fuel inlet nozzle opening into the narrowest part of the venturi and means for lowering the fuel inlet nozzle as the capacity of 50 the venturi is increased.

4. The combination with a fuel mixture passageway, of interconnected throttle valves therefor adapted to open said passageway, a lever connected to the axis of one of said valves, a rod movable in one direction to engage the lever and close the valves and movable in the opposite direction to release the lever, the opening movement of the valves being completed by the velocity of the mixture stream passing therethrough.

5. The combination with a fuel mixture passageway, of interconnected throttle valves therefor adapted to open said passageway, a lever connected to the axis of one of said valves, a rod movable in one direction to engage the lever and close the valves and movable in the opposite direction to release the lever, the opening movement of the valves being completed by the velocity of the mixture stream passing between them, and a dash pot, with a bleed, connected to 70 said lever.

6. The combination with a fuel mixture passageway, of throttle valves therein adapted to open at the center of the passageway, one of said valves having a fuel duct with small orifices at 75

- the inner edge and at the axis of the valve respectively, the other valve having a fuel duct with a single larger orifice located at the axis of the valve.
5. The combination with a fuel mixture passageway having an air inlet formed with an annular valve seat, of a reciprocable choke valve cooperating with said seat and adapted to be opened by suction through said passageway, a spring opposing the opening of said valve, a second spring, and means for setting said second spring to oppose the first mentioned spring when a full choke is not desired.
8. The combination with a fuel mixture passageway having an air inlet formed with an annular valve seat, of a reciprocable choke valve cooperating with said seat and adapted to be opened by suction through said passageway, a spring opposing the opening of said valve, a second spring normally idle when full choke is desired, and manually operable means to set said second spring to exert different degrees of opposition to the first mentioned spring as circumstances require.
9. The combination with a fuel mixture passageway having an air inlet formed with an annular valve seat, of a reciprocable choke valve cooperating with said seat and adapted to be opened by suction through said passageway, a spring opposing the opening of said valve, a second spring normally idle when full choke is desired, and a manually operable cam directly engageable with said valve to positively open it when choking is not desired.
10. In a carburetor, an intake passageway having an air inlet, two throttle valve members within the passageway with a variable opening between them, and fuel jets discharging in converging lines toward the center of the air stream directly between said valves.
